Nicholas Müller's Design for a **CLOCK.CASE**

No. 5,892.

Patented June 4, 1872.

*Wm. G. Müller, Nichola Müller
A. P. Ackersonberg*

UNITED STATES PATENT OFFICE.

NICHOLAS MÜLLER, OF NEW YORK, N. Y.

DESIGN FOR A CLOCK-CASE.

Specification forming part of Design No. 5,892, dated June 4, 1872.

To all whom it may concern:

Be it known that I, NICHOLAS MÜLLER, of the city, county, and State of New York, have invented a new and ornamental Design for a Clock-Case; and I do hereby declare that the following is a full, clear, and exact description of the same which will enable those skilled in the art to make and use the same, reference being had to the accompanying photograph forming part of this specification, in which a perspective view of the design is given.

This case in its general design somewhat resembles a Gothic chapel. The sharp, roof-shaped top is supported by four columns, these

columns resting on the base or lower portion of the design. Arabesques and other ornamental figures embellish the front and sides of the design, (the sides being alike,) as seen in the photograph.

What I claim as my invention, and desire to secure by Letters Patent, is—

The design for a clock-case, as herein shown and described.

Signed by me this 19th day of April, 1872.

NICHOLAS MÜLLER.
In presence of—
W.M. F. MÜLLER,
J. P. AECKERSBERG.
